UNITED STATES PATENT OFFICE.

ALBERT I. APPLETON, OF CHICAGO, ILLINOIS, ASSIGNOR TO APPLETON ELECTRIC COMPANY, OF CHICAGO, ILLINOIS, A CORPORATION OF ILLINOIS.

OUTLET-BOX.

051,942.

Specification of Letters Patent.

Patented Feb. 4, 1913.

Application filed August 21, 1909. Serial No. 513,940.

To all whom it may concern:

Be it known that I, ALBERT I. APPLETON, a citizen of the United States, residing at Chicago, in the county of Cook and State 5 of Illinois, have invented certain new and useful Improvements in Outlet-Boxes, of which the following is a specification.

This invention relates to the outlet boxes used in electric wiring systems to contain switches, fuse boxes, and the like.

One of the objects of the invention is to provide means for conveniently connecting together the sections of a sectional outlet box.

Another object is to produce improved means for obtaining outlet boxes of various lengths.

Another object of the invention is to provide improved means for securing together 20 the walls of an outlet box.

A further object is to provide improved means for securing the box in place in the wall of a building or other structure.

In the accompanying drawings, Figure 1 25 is a perspective view of an outlet box embodying the features of my invention. Fig. 2 is a perspective view of a section of said box. Fig. 3 is a fragmental side elevation of the box. Fig. 4 is a fragmental front elevation of the box, with portions in section. Fig. 5 is a sectional view taken in the plane of dotted line 5-5 of Fig. 3. Fig. 6 is a plan view of the box section shown in Fig. 2, with portions thereof in section. Fig. 7 35 is a view illustrating one of the two positions which the box-attaching means may occupy with relation to the box. Figs. 8 and 9 are detail views of two different methods of connecting together the walls 40 of an outlet box or box section. Figs. 10 and 11 are perspective views illustrating a box-attaching means.

The embodiment herein shown of my invention comprises two box sections A and 45 B, which are substantially similar, save that one is longer than the other. Said sections are provided with means for connecting them together, the connecting means being of such nature that a long and a short 50 section may be connected to provide a box of a given length; or two short sections may be secured together to form a shorter box; or two long sections may be united to provide a box of greater length than the given 55 length.

Referring now to Fig. 1: The box-section A comprises the side walls 1 and 2, the rear wall 3 and the end wall 4. The box-section B comprises the side walls 1^a and 2^a, the rear wall 3^a and the end wall 4^a. The means 60 herein shown for connecting together the box-sections A and B in any desired combination comprises a flange 5 formed upon one edge of each of the walls 2 2^a of said sections, said flange having at its middle 65 portion upon one edge thereof a hook 6 adapted to engage a screw 7 seated in each of the walls 1 1^a of said sections. The flanges 5 are preferably formed integral with the side walls 2 2^a and are bent to lie 70 in planes substantially parallel with said side walls. As will be apparent from Fig. 1, each box-section has a screw 7 in one side wall and a hook 6 on the other side wall, the hooks being placed upon the corresponding sides of all sections. It will thus be seen that any two box-sections may be secured together, the hook 6 of each section 75 engaging a screw 7 of the other section. When the screws 7 are tightened up the 80 hooks 6 will be clamped against the adjacent side walls, and the box-sections rigidly secured together. The flanges 5 are of sufficient width and length to prevent relative displacement of the box-sections through 85 twisting stresses.

It will be seen that a workman supplied with box-sections A and B can assemble a box of the desired length by operating two 90 screws only. The screws need not be removed when the sections are to be separated, it being sufficient to loosen the screws enough to permit of withdrawing the hooks 6. In assembling a box, the hooks 6 are slipped onto the screws 7 and the latter 95 tightened up.

The side and end walls of each box-section are preferably formed of an integral piece of sheet metal. The rear wall 3 or 3^a may be secured to the side and end walls by 100 means to be next described.

The rear wall overlies the edges of the side and end walls. Upon opposite edges of the rear wall and near one edge thereof are formed angular lugs 8 arranged to lie at the 105 inner sides of the side walls, as shown in Figs. 2, 4 and 6. On the edges of the rear wall from which the lugs 8 are bent up, are angular tongues 9 which are adapted to be bent to enter openings 10 (Fig. 8) in the ad- 110

jacent portions of the side walls. It will be seen that the lugs 8 and the tongues 9 constitute a simple, yet efficient, means for rigidly connecting together the rear and side walls of the box.

5. Instead of bending the upper ends of the tongues 9 into the openings 10, as just described, said tongues may be of sufficient size, as shown in Fig. 9, to overlie the opening and to permit of forcing a portion 11 of the tongue into said opening.

The box may be secured in place in any suitable manner. I have herein shown each box-section as provided with a suitable number of pairs of perforated ears 12, each pair of ears being formed integral with a base 13. In the end portions of the base 13 are openings 14 to receive angular lugs or hooks 15 formed upon the side walls of the box-sections. The hooks 15 for each pair of attaching ears face in the same direction and are of such form as to overlie the base 13 adjacent to the openings 14 through which the hooks extend, as shown in Figs. 3 and 4. 15. The base 13 is secured against removal from the hooks 15 by means of a stud 16 formed upon the base 13 adjacent to one of the openings 14. As will be understood from Fig. 2, said stud may be bent to lie behind the adjacent hook 15 and thereby prevent the base 13 from being removed from said hooks.

It is sometimes desirable to attach the supporting ears 12 to the box with said ears lying substantially flush with the front side 35 of the box, and at other times to attach the ears to the box so that they are spaced rearwardly from the front of the box, as shown in Fig. 7. The base 13 may be placed upon the hooks 15 so that the ears shall occupy 40 either of the two positions just described. Two studs 16 are provided adjacent to one of the openings 14 in each base 13 in order that one of said studs shall be in position for bending behind a hook 15, whichever position 45 the ears 12 may occupy, as will be clear from a comparison of Figs. 3 and 7.

Conduits may be connected with the box in any preferred manner. I have herein shown openings 17 in the side and rear walls 50 of the box, which openings are normally closed by plugs 18.

Switches, etc., may be mounted in the box by any desired means, as, for example, perforated, threaded ears 19, formed on the side 55 walls of the box.

No undue limitation should be understood from the foregoing detailed description, for the present embodiment is susceptible of various modifications without departing from 60 the spirit of the invention.

I claim as my invention:

1. An electric outlet box comprising two sections, and means for connecting said sections together, consisting of a single hook 65 on each section and a single screw on each

section, the hooks being adapted to be slipped beneath the heads of the screws, and the screws clamping the hooks against the adjacent portions of the sections.

2. An electric outlet box comprising two 70 sections and means for connecting said sections together, consisting of a single flange on each section, each flange having a hook thereon, and a projecting part on each section, the hooks being adapted to engage said 75 projecting parts, said flanges overlying the adjacent portions of the sections and assisting to prevent relative displacement of the sections.

3. An electric outlet box consisting of two 80 body sections of unequal length, and means for connecting said sections together.

4. An electric outlet box having a box-supporting device, said device comprising an apertured portion, a hook on the box 85 adapted to enter said apertured portion, and means to prevent withdrawal of said hook from said apertured portion.

5. An electric outlet box having a box-supporting device, said device comprising 90 an apertured portion, a device on the box adapted to enter said apertured portion, and means on said apertured portion for preventing withdrawal of the second mentioned device from said apertured portion. 95

6. An electric outlet box having a box-supporting ear, said ear having a base provided with an opening and a stud near said opening, said box having a hook thereon adapted to enter said opening, said stud being adapted to be bent to lie adjacent to said hook to prevent its withdrawal from said opening.

7. An electric outlet box, a box-supporting device having a base provided with 105 two openings and two studs near one of said openings, said box having two hooks thereon adapted to enter said openings, each of said studs being adapted to be bent to lie behind one of said hooks to prevent its withdrawal 110 from its opening.

8. A structure comprising two metal walls, one of said walls having an opening therein, and the other wall overlying the edge of the first mentioned wall and having 115 a lug bent at substantially a right angle, the outer end of said lug lying in said opening.

9. A structure comprising two opposite walls and a third wall, said third wall having 120 lugs which lie at the inner sides of said opposite walls, each of said opposite walls having an opening therein, said third wall having lugs which lie at the outer sides of said opposite walls and enter said openings. 125

10. A structure comprising two side walls, an end wall integral with said side walls, a rear wall overlying the edges of said other walls, lugs on said rear wall at the inner faces of the side walls said side walls having 130

openings therein, and lugs on said rear wall at the outer faces of the side walls and entering said openings.

11. An electric outlet box consisting of two body sections, each comprising two side walls and a rear wall, the side walls and rear wall of one section being longer than those of the other section, said sections being fitted together with the free edges of said side and rear walls abutting; and interengaging parts carried by the respective sections for securing said sections together.

12. An electric outlet box comprising a

plurality of body sections, each having two side walls and a rear wall, each of said sections having a hook at the edge of one of its side walls, and a projection at the edge of its other side wall, whereby the hook and the projection of any section is adapted to be interlocked with the hook and projection on any other section. 15 20

ALBERT I. APPLETON.
